UNITED STATES PATENT OFFICE.

OTTO W. SCHAUM, OF PHILADELPHIA, PENNSYLVANIA.

DESIGN FOR A VIBRATOR-GEAR FOR SHEDDING MECHANISMS.

SPECIFICATION forming part of Design No. 83,832, dated January 1, 1901.

Application filed December 6, 1900. Serial No. 38,964. Term of patent 14 years.

To all whom it may concern:

Be it known that I, OTTO W. SCHAUM, a citizen of the United States, residing in Philadelphia, in the county of Philadelphia and State of Pennsylvania, have invented a new and useful Design for Vibrator-Gears for Sheding Mechanism; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

Referring to the accompanying drawings, Figure 1 is a view in side elevation of a vibrator gear or pinion constructed in accordance with my invention. Fig. 2 is a plan view of the device, and Fig. 3 is a longitudinal sectional view on the line xx in Fig. 2.

As essential features of design the vibrator gear or pinion which is the subject of the said design comprehends in its construction a toothed substantially circular body portion and an integral radial arm, said body portion and the arm being penetrated by openings, the former centrally.

a designates the body portion, the same being substantially circular and having on the greater part of its periphery a series of teeth b . The said body portion is provided centrally with an orifice or opening c . On each

of its faces and surrounding the said opening is an annular boss d , the effect of which is to thicken the body portion annularly about the opening.

e denotes the radial arm portion. The width of this arm is slightly greater than that of the orifice in the body portion. One face of this arm is cut away, as at f , thus reducing the thickness of the arm.

The arm is provided with an orifice or opening g , which is approximately of the size of the orifice or opening c in the body portion. Surrounding this orifice or opening g and on the face of the arm which is opposite the face thereof which is cut away is an annular boss h .

i designates an annular recess, which is formed in the arm inside of the boss and communicating with the orifice or opening g .

Having thus fully described my invention, what I claim as new, and desire to secure by Letters Patent, is—

The design for a vibrator-gear for a shedding mechanism substantially as herein shown and described.

In testimony that I claim the foregoing I have hereunto set my hand this 22d day of November, 1900.

OTTO W. SCHAUM.
